No. 692,220.

Patented Jan. 28, 1902

E. S. WAHMAN & H. A. REHBERG.

PEG CUTTER.

(Application filed Feb. 16, 1900.)

(No Model.)

UNITED STATES PATENT OFFICE.

ERNEST S. WAHMAN AND HENRY A. REHBERG, OF BELOIT, WISCONSIN,
ASSIGNORS TO HARVEY EDWARD NICHOLS, ORION D. W. INMAN, AND
CLARENCE W. INMAN, OF BELOIT, WISCONSIN.

PEG-CUTTER.

SPECIFICATION forming part of Letters Patent No. 692,220, dated January 28, 1902.

Application filed February 16, 1900. Serial No. 5,614. (No model.)

To all whom it may concern:

Be it known that we, ERNEST S. WAHMAN and HENRY A. REHBERG, citizens of the United States of America, residing at Beloit, in the county of Rock and State of Wisconsin, have invented certain new and useful Improvements in Nippers, of which the following is a specification, reference being had therein to the accompanying drawings.

10 This invention relates to certain new and useful improvements in nippers, and relates more specifically to that class of nippers which are employed for removing or cutting nails or pegs in the insoles of shoes and the like.

15 The object of the invention is to construct an improved nippers of this class by means of which the nail or peg may be cut off close to or below the surface of the insole; furthermore, to so construct the nippers that they may be employed for grasping the nail or peg in such a manner that the same may be dragged forward into position for cutting the same more advantageously, or, if desired, 20 to entirely remove such nail or peg from the shoe or the like.

25 A further object of the invention is to construct nippers of this class with jaws of especial form, one being practically straight, so that it may be forced under pressure into the insole and will rest against the nail at a point considerably below the protruding tip thereof, and the other of which jaws is curved in such a manner that when closed against the nail or peg its knife-edge will in describing the 30 arc of its circle close toward and pass under the knife-edge of the straight jaw to effect a clean sharp cut of the nail or peg.

35 Briefly described, therefore, our invention 40 comprises two pivoted handles curved with respect to each other, that the desired cutting effect of the jaws may be obtained, these handles being pivoted and adapted to close one against the other, with the one handle constructed with a practically straight knife-edge and the other with a curved knife-edge, the 45 knife-edge of the straight jaw being adapted to pass beyond the plane of the knife-edge on the curved jaw and lie slightly within such

curved jaw when the jaws are closed. All of 50 this construction will be hereinafter more specifically described and then particularly pointed out in the appended claim, and in describing the invention in detail reference will be had to the accompanying drawings, 55 forming a part of this specification, wherein like numerals of reference will be employed to designate similar parts throughout these several views of the drawings, and in which—

Figure 1 is a side view of our improved nippers, showing a part of a shoe in longitudinal section, with the nippers in position for cutting a nail or peg in the insole thereof. Fig. 2 is a top plan view of our improved nippers when in the closed position. Fig. 3 is a detail perspective view of the jaws and a part of the handles, the latter being separated and pivot removed to clearly illustrate the construction at point of pivot. Fig. 4 is a detail side view of the jaws when in the closed position with the handles broken away.

55 In the construction of our improved nippers the same are preferably made from the best-tempered steel, in order that a knife-edge of sufficient hardness and strength may be obtained on the jaws for use in cutting iron, 60 steel, or other metallic nails.

65 The nippers consist of two members, which may be termed "handles" or "levers," as they act in the capacity of both such elements. Referring to the drawings, we will first describe what we will term the "upper" handle or lever 1, which is essentially a flat bar of 70 steel or other suitable metal and is preferably given the curvature as shown for convenience 75 of operation in the interior of a shoe or the like. We preferably provide this upper lever on its outer end with a handle 2, though such handle may be dispensed with, if desired. Near its inner end this upper lever or 80 handle is shouldered, as at 3, and has the curved face 4 on its end, terminating in the knife-edge 5. The width of the curved face 4 is equal to the combined width of the two members at the point where they are pivoted 85 together, and to permit of a wide opening or separating of the jaws the upper edge of the lever or member 1 is inclined, as at 6, so that

such member may not lock against the curved jaw of the other member when the jaws are being opened or separated. (See Fig. 1.) The other member 7 we will term as the "lower" lever or handle and has a curve approximately the same as that of the member 1 or upper lever, and for convenience in operating the tool is slightly less in length than the combined length of the upper lever and its handle 2. 5
10 This lower lever 7 likewise consists of a flat bar throughout that portion of the same which closes flat against the member or upper lever 1 when the jaws are closed; but its outer or "gripping" end is preferably flattened at right angles to the part of the lever which engages the upper lever 1, so as to form a convenient grip for the hand of the operator. At its inner end this lower member terminates in a curved jaw 8, having a knife-edge 9, adapted 15
20 when the jaws are closed to lie slightly below the plane of the knife-edge 5, as shown in Fig. 4 of the drawings, so that these knife-edges when the jaws are closing will effectually cut nails or the like. The width of this 25 curved jaw is the same as that of the straight jaw or equal to that of the upper and lower lever at the pivotal point thereof, the curved jaw having a lip or lug 10, which lies over the incline 6, the edge of such lip or lug being at 30 different inclines, as at 11 and 12, respectively, so as to permit the extreme opening of the jaws. The free inner end of this lever 7 is shouldered, as at 14, to conform to the shoulder 3 of the upper lever. The levers are both 35 provided, close to the jaws, with apertures 15, adapted to register, and in which is placed the pivotal pin or screw 16, upon which the levers operate and by which they are held together.

We will now describe the operation, and in 40 practice have found that a convenient manner of using the tool is to hold the shoe or other article in the left hand, with the nippers placed inside the shoe, the flat surface of the lower jaw against the insole and the 45 knife-edge against the tip of the nail or peg to be removed, with the handle 2 against the breast of the operator. The lower jaw, with the knife-edge 5, is pressed against the insole at the nail or peg to be cut off at such an angle as the operator desires, as illustrated at 50 17, Fig. 1 of the drawings, and the upper jaw of the nippers is then pressed downward with

the right hand, cutting off the tip of the nail or peg at the depth desired in the insole.

We desire to call particular attention to 55 the fact (for illustration see Fig. 4) that the upper or curved jaw does not meet the lower jaw, but cuts by and under it, and when closed can be used for grasping or hooking onto the nail or peg and pulling forward the 60 tips of the same into position for cutting any nails or pegs bent forward or away from the operator.

It will be observed that various changes 65 may be made in the details of construction without departing from the general spirit of our invention.

Having thus fully described our invention, what we claim as new, and desire to secure by Letters Patent, is—

In a device of the character described, a pair of curved levers, a handle secured to the extremity of one of said levers, the other of said levers having its extremity flattened, the other end of each of said levers having 75 an enlarged portion forming a shoulder, said enlarged ends being of a width equal to the combined thicknesses of said levers, the said shoulders each having an inclined face, one of said faces being of less incline than the 80 other, a pivotal connection between said levers slightly to the rear of said shoulders, curved jaws made integral with said shoulders and of the same width as the said shoulders, oppositely-disposed curved inner faces 85 on said jaws, one of said curved faces being of greater curvature than the other and adapted to have its edge extend beyond said lesser curved jaw when the device is closed, whereby the jaw of lesser curvature may engage 90 the nail at a point approximately in alignment with the insole and the other engage the nail at a point below the surface of said insole, when the lever connected to said first-named jaw is pressed upward cutting the nail 95 below the surface of said insole, substantially as described.

In testimony whereof we affix our signatures in the presence of two witnesses.

ERNEST S. WAHMAN.
HENRY A. REHBERG.

Witnesses:

JONAS INMAN,
O. D. INMAN.
